[57]**CLAIM**

The ornamental design for a connector module, as shown and described.

DESCRIPTION

FIG. 1 shows a front and upper right perspective view of a connector module showing our new design; FIG. 2 shows a front elevation view thereof; FIG. 3 shows a bottom plan view thereof; FIG. 4 shows a rear elevation view thereof; FIG. 5 shows a right side elevational view thereof, the left side elevational view being a mirror image; FIG. 6 shows a top plan view thereof; and, FIG. 7 shows a rear and upper left plan view perspective view of a connector module showing our new design. The designations indicated by broken lines in FIGS. 1 and 2 are illustrated by way of example only, as such will be dictated by the particular application of the connector assembly, and such designations are not a part of the design claimed herein.
